United States Patent Office

Des. 183,511

Patented Sept. 16, 1958

183,511

STAND FOR A PORTABLE FOOD MIXER

Robert A. Chesney, Youngstown, and Earl J. Chesney,
Struthers, Ohio

Application March 10, 1958, Serial No. 49,961

Term of patent 3½ years

(Cl. D44—29)

We claim:

The ornamental design for a stand for a portable food mixer, as shown.
